MARTIN L. GROVE, OF TYLERSBURG, PENNSYLVANIA. ASSIGNOR OF ONE-HALF TO
WILLIAM ALEXANDER WRAY AND ONE-SIXTH TO ALBERT FOY, BOTH OF TYLERS-
BURG, PENNSYLVANIA.

GASOLENE-STRAINER.

1,155,914.

Specification of Letters Patent.

Patented Oct. 5, 1915.

Application filed September 9, 1914. Serial No. 860,881.

To all whom it may concern:

Be it known that I, MARTIN L. GROVE, a citizen of the United States, residing at Tylersburg, in the county of Clarion and State of Pennsylvania, have invented a new and useful Gasolene-Strainer, of which the following is a specification.

The invention relates to improvements in gasolene strainers.

10 The object of the present invention is to improve the construction of gasolene strainers and to provide a simple, practical, and efficient gasolene-strainer, designed particularly for use on motor vehicles, motor boats, 15 and the like, and adapted to be readily placed in a straight pipe line between a gasolene tank and a carbureter, and capable of filtering the gasolene and of straining the impurities and sediment, as well as separating 20 the water, therefrom, and which may be cleaned without removing the strainer from its position in the pipe.

With these and other objects in view the invention consists in the construction and 25 novel combination of parts hereinafter fully described, illustrated in the accompanying drawing, and pointed out in the claims appended hereto, it being understood that various changes in the form, proportion, size 30 and minor details of construction, within the scope of the claims, may be resorted to without departing from the spirit or sacrificing any of the advantages of the invention.

35 In the drawing:—Figure 1 is a side elevation of a gasolene strainer constructed in accordance with this invention. Fig. 2 is a central longitudinal sectional view of the same. Fig. 3 is a central transverse sectional view of the strainer. Fig. 4 is a detail sectional view of the cap nut, illustrating the arrangement of the filtering material.

Like numerals of reference designate corresponding parts in all the figures of the 45 drawing.

In the accompanying drawing, in which is illustrated the preferred embodiment of the invention, 1 designates a horizontal tubular body or casing of substantially cylindrical form, open at one end 2 and provided at the other end with an integral end wall 3 having a threaded opening 4, preferably in the form of a nipple, as shown, and adapted to receive an inlet pipe 5. The 55 body or casing 1 is provided at an inter-

mediate point with a depending downwardly tapered trap extension 6 having a substantially cylindrical lower terminal portion 7, which is interiorly threaded at 8 for the reception of a removable screw plug 9. 60 The screw plug 9, which is threaded at 10 to engage the threads of the trap extension, is provided with an annular flange 11, and it has a squared wrench receiving portion 12. The flange 11 fits against the lower edge of 65 the trap extension and the plug is provided at the top with a recess or concavity 13, adapted to lighten the structure and at the same time form a cup for holding the impurities accumulating within the trap extension. The open end 2 of the casing is interiorly threaded for the reception of an 70 exteriorly threaded portion 13^a of a hollow cap nut 14, provided with a central threaded opening 15, preferably in the form of a 75 threaded nipple, and arranged in horizontal alinement with the threaded opening 4 and receiving the threaded end 15^a of an outlet pipe 16. As the threaded openings of the end wall 3 and the cap nut 14 are in horizontal alinement, the strainer is adapted to be 80 readily applied to various types of automobiles and other motor vehicles.

The hollow nut is provided with a plurality of interior annular recesses 17 and 18 85 of different diameters forming shoulders or seats 19 and 20. The recess 18 is arranged in spaced relation with the end wall of the cap nut to provide an annular space 21, which is of less diameter than the recess 18. 90 The space 21 is adapted to contain a quantity of free gasolene or other liquid and it insures a proper supply for the same and at the same time permits free action of the device in straining the gasolene. The shoulder 19 forms a seat for a chamois straining disk 22 and a screen 23, which are retained in place by a resilient ring 24 engaging an annular groove 25 in the walls of the recess 17. The retaining ring, which is constructed of a single piece of resilient wire or other suitable material separated at its ends 26, as clearly illustrated in Fig. 3 of the drawing, is adapted to be readily sprung into and out of engagement with the groove, 105 and it engages the screen and securely holds the same and the chamois straining disk on the shoulder or seat 19. The screen 23, which is constructed of woven wire, is adapted to strain the impurities from the gaso- 110

lene, and, with the chamois disk, is capable of separating the water and sediment. The recess 18 is provided for the purpose of enabling any other suitable additional filtering material, as shown at 28 in Fig. 4 of the drawing, to be employed and to be retained in place by the fastening means for securing the screen.

While the strainer is designed particularly for removing the sediment, impurities, and water, from gasoline, it may be employed for other purposes, and the packing receiving recess or space 18 will enable the proper filtering material to be placed in the cap nut for adapting the device for any desired use. The combined cup and closure plug 9 is adapted to catch and retain the sediment and impurities, and when removing the plug, such accumulation may be retained in the recess while the liquid may be caught in a suitable receptacle placed beneath the casing. The pipes 5 and 16, with which the casing is connected, are provided with suitable unions 27 for enabling the strainer to be readily placed in and removed from the pipe line.

The invention as above set forth is distinguished from prior constructions in at least two particulars. First, it will be noted upon reference to Fig. 4 that the filtering material 28 is retained in place by the disk 22 and screen 23 and that the latter are in turn held in position by the retaining ring 24. Said retaining ring therefore constitutes a single retaining means for the straining or filtering medium when the cap is in or out of position.

I am aware that it is old in filters to provide stepped screens and this I do not broadly claim. The novelty of this part of the present invention resides in the fact that by reason of the position of the parts 22, 23 and 28 with relation to the retaining ring the latter serves to hold said three parts in position within the cap.

The second feature resides in the location of the filtering medium in a cap provided at the outlet end of the casing so that it is not necessary to remove the casing when it is desired to clean the strainer. It can be readily seen that the cap 14, which is in the form of a hollow nut, may be readily unscrewed from the casing without detaching the other end of the casing from the pipe line, or without separating the casing itself from its position in the line of piping between the gasoline tank and the carburetor. By applying a wrench to the hollow cap nut 14, the latter may be unscrewed from the casing without disturbing any of the other parts of the casing. This is made possible by reason of the fact that a union joint connects the short section of the pipe 16 with the adjacent end of the pipe line. Moreover, when the hollow cap nut is removed,

it carries with it the straining and filtering medium intact, and yet it takes but a moment to remove the filtering material, straining disk and the screen from their respective positions within the cap nut after the retaining ring has been detached. Another advantage in having the straining and filtering medium applied to the hollow cap nut lies in the fact that should large chunks of dirt pass through the inlet pipe 5 they will not reach the screens but will gravitate to the bottom of the casing by reason of the position of the depending trap extension 6, and may then be removed through the screw plug 9. There is therefore a clear advantage in providing the straining and filtering medium in the hollow cap nut in the manner herein described and shown.

What is claimed is:—

1. In combination with inlet and outlet pipes each having a pipe union therein, a horizontally disposed tubular casing provided at one end with an opening for the connection of the inlet pipe thereto and having its other end open and interiorly threaded, said casing being also provided between its ends with a depending downwardly tapered extension having its lower end open, a removable closure for said open end, an exteriorly threaded hollow cap nut screwed into and closing the open end of the casing and having an opening for the connection of the outlet pipe thereto, said cap nut being provided with a plurality of interior annular recesses of gradually increasing diameters forming seats, a straining means located wholly within and carried by the cap nut and mounted in said seats, a removable fastening ring also located within the cap nut for retaining the straining means in place, whereby any foreign matter passing through the inlet pipe is caught by the trap extension and prevented from passing through the straining means, the removability of the cap nut permitting the strainer to be cleaned without disconnecting the entire device from the pipe line.

2. A gasoline strainer including a horizontally disposed tubular casing provided at one end with an opening for the inlet pipe and having its other end open and interiorly threaded, said casing being also provided between its ends with a depending trap extension, an exteriorly threaded hollow cylindrical cap nut screwed into and closing the open end of the casing and having an opening for the outlet pipe, said cap nut being provided with a plurality of interior annular recesses of gradually increasing diameters forming seats, a straining and filtering medium located wholly within and carried by the cap nut and consisting of a straining disk and a screen arranged on the seat of the outer annular recess, the inner annular

recess being adapted to receive filtering material which is held in place by the disk and screen, and a fastening ring located within an interior groove of the cap for retaining the disk and screen in place thereby serving to hold the entire straining and filtering medium in position when the cap is either on or off the casing.

In testimony, that I claim the foregoing as my own, I have hereto affixed my signature in the presence of two witnesses.

MARTIN L. GROVE.
